UNITED STATES PATENT OFFICE.

ABBOT AUGUSTUS LOW, OF BROOKLYN, NEW YORK.

DESIGN FOR A SAP-PAIL COVER.

SPECIFICATION forming part of Design No. 34,539, dated May 21, 1901.

Application filed January 29, 1901. Serial No. 45,252. Term of patent 14 years.

To all whom it may concern:

Be it known that I, ABBOT AUGUSTUS LOW, a citizen of the United States, residing in the city of New York, borough of Brooklyn, county of Kings, and State of New York, have invented and produced a new and original Design for Sap-Pail Covers, of which the following is a specification, reference being had to the accompanying drawings, forming a part thereof.

Figure 1 is a plan of a sap-pail cover, showing my design. Fig. 2 is an edge view of the same; and Fig. 3, a section upon plane of line 3 3, Fig. 1.

As shown in the accompanying drawings,

the leading or material feature of my design consists of the rim *a*, eccentric to the body *A* of the cover, the said eccentric rim *a* being formed with the perforation *a'* at its widest part, as clearly illustrated in Fig. 1.

20

Having described my design, what I claim as new, and desire to secure by Letters Patent, is—

The design for a sap-pail cover as herein shown and described.

ABBOT AUGUSTUS LOW.
